CAN BODY STRAIGHTENING MACHINE

Alois G. Luthi, Gardena, Calif., assignor to Luthi Machinery & Engineering Co., Inc., Gardena, Calif., a corporation of California

Application October 28, 1955, Serial No. 543,353

3 Claims. (Cl. 153—54)

This invention relates to can body straightening machines, and more particularly to a machine for smoothing out dents in the walls and edges of damaged can bodies prior to the filling thereof. The present application is a continuation-in-part of my prior application Serial No. 403,227, entitled, "Can Straightening Machine," filed January 11, 1954, now abandoned.

It is among the objects of this invention to provide a machine by which dented can bodies may be straightened to usable condition.

Another object of the invention is to provide a machine adaptable for use with a variety of sizes and shapes of bodies, and in which the various parts may be adjusted in conformity with the can bodies to be treated.

A further object is to provide a machine by which dents may be removed from a flanged open end of a can body as well as from the wall portion proper.

It is also an object to provide a machine in which pressure is applied to move a can body axially onto a mandrel in conjunction with the movement of straightening rollers against the side walls of the can.

A still further object is to provide a machine in which can bodies may be placed upon a power driven mandrel by mechanism manually controlled to engage and disengage cans carried by the mandrel.

The invention has other objects and features of advantage, some of which, with the foregoing, will be explained in the following description of that form of the invention illustrated in the drawings. It is to be understood that the invention is not limited to the embodiment shown in the drawings, as the device may be embodied in other forms within the definition of the claims.

In the drawings,

Fig. 1 is a side elevation of a can body straightening machine embodying my invention, parts being broken away and parts being shown in section;

Fig. 2 is a front elevation of the machine shown in Fig. 1, the mandrel being omitted;

Fig. 3 is a plan view of the machine;

Fig. 4 is a fragmental sectional view with the smoothing rollers in an intermediate position, the plane of the section being indicated by the line 4—4 of Fig. 3;

Fig. 5 is a fragmental sectional detail view, the plane of the section being indicated by the line 5—5 of Fig. 1.

In terms of broad conclusion, the can body straightening machine of this invention comprises a power driven rigid mandrel shaped to conform to the interior of a can body and a pair of straightening rollers movable to press the can body against the mandrel for removing dents from the can body wall. The mandrel is provided with a rim against which the expanded edge of a can body may be pressed by the ends of said pair of rollers for removing dents from the edge. A can body holding roller is mounted for pivotal movement in conjunction with the straightening rollers. The holding roller is mounted for rotational movement about an axis at right angles to the axes of said pair of rollers and is adapted to yieldably press the can body downwardly onto the man-

2

drel as it is rotated thereby past the pair of straightening rollers.

The invention contemplates a unit in which a mandrel of desired size and shape, may be replaceably mounted upon a power driven shaft for straightening cans of various sizes and shapes, the mounting means for the straightening rollers and the can body holding roller each being adjustable to conform to the various sizes of mandrel.

10 In terms of greater detail, the device of the present invention comprises a base frame 10 within which is housed a motor 12 geared to a power-driven mandrel shaft 13. The shaft 13 is mounted in a vertical position by suitable bearings 14 set within the ends of housing extensions 15 and 16 below and above the top wall of the housing frame 10, respectively, as best shown in Fig. 1 of the drawings. The motor 12 is preferably connected to the shaft 13 by means of a worm 17 secured to the motor shaft and meshing with a gear 18 secured to the lower end of the shaft 13.

Upon the upper end of the driven shaft 13 is removably mounted a mandrel 19, keyed or otherwise replaceably secured to the shaft and driven thereby, and arranged to receive a can body 20. The mandrel 19 is axially recessed to seat upon the upwardly extending end of the power driven shaft 13. The lower end of the mandrel 19 is provided with a rim 21 and a smooth and accurately finished fillet 22 which extends entirely around the mandrel at the juncture of the mandrel 19 and rim 21. It is contemplated that the mandrels 19 will be made to conform to the interior of can bodies 20 of various sizes and shapes, a selected mandrel being mountable upon the shaft 13 to conform to the size and style of the can body to be straightened.

15 The frame 10 is provided with an upwardly extending bracket 24, bolted or otherwise suitably secured to the base frame 10, in spaced relation to the shaft 13. A carriage member 26 is adjustably mounted upon the bracket 24. As illustrated, the carriage member 26 is provided with a stem 27 extending horizontally through a bearing portion 28 formed upon the back of the bracket 24. The axis of the stem 27 and bearing 28 is positioned to intersect the axis of the mandrel 19 and shaft 13 at right angles. Pins 29, upon opposite sides of the carriage 26, extend outwardly through slots 31 formed in the side of the bracket 24. Nuts 32, or other suitable securing means, are provided for securing the carriage in adjusted position upon the bracket to conform to various sizes of mandrels placed upon the shaft 13.

20 A pair of can body straightening rollers 34 are journaled between arms 35 and 35a at the upper and lower ends, respectively, of a mounting frame designated in general by the numeral 36. The frame 36 is pivotally connected to the carriage 26 by means of upper and lower connecting links 37 and 38, respectively. The upper links 37 are pivotally connected to the carriage 26 by means of pivot pins 39, and to the frame 36 by pivot pins 40. The lower links 38 are secured to a shaft 41 extending transversely across the bottom portion of the carriage 26. The free ends of the lower links 38 are pivoted to the frame 36 near its lower end by pivot pins 42. The distance between the center of the pivot pins 39 and 40 is equal to the distance between the center of the shaft 41 and the center of the pivot pin 42. The frame 36 is supported upon the lever links 37 and 38 and is movable thereby along an arcuate path without being moved out of parallelism with the shaft 13 and mandrel 19. An actuating lever arm 43 is secured to the shaft 41 at one side of the bracket 24 for manually actuating the lower links 38 and the frame 36.

In order to hold the can body 20 downwardly on the

mandrel 19, a roller 44 is adjustably mounted on the frame 36 and is adapted to press downwardly on the upper edge of the can body. The roller 44 is rotatably mounted on a bracket 45 slidably received in a vertical slot 46 formed in the front face of a vertical post 47 fixed to the frame 36. A stud 48 extends through a longitudinally extending slot 49 in the bracket 45 and is threadedly received in any one of a plurality of holes 50 spaced longitudinally along the post 47.

In operation, a mandrel 19, of a size conforming to the can bodies 20 to be straightened, is placed upon the driven shaft 13. The carriage 26 is then adjusted upon the bracket 24 to a position such that the rollers 34 carried by the frame 36 may be moved pivotally by the actuating arm 43 to engage a can body 20 upon the mandrel 19 in the manner illustrated in Fig. 1 of the drawings. While the shaft 13 and mandrel 19 are being rotated at a reduced speed by the motor 12 through the worm 17 and worm gear 18, the actuating arm 43 is swung upwardly through an angle of about 45° to 60° . This causes a corresponding rotation of the shaft 41 and a corresponding pivotal movement of the lower frame supporting links 38, thereby causing the roller supporting frame 36 to be moved upwardly and away from the mandrel to a position such as indicated in Fig. 4 of the drawings. Since the frame 36 is linked to the carriage at top and bottom by connecting links of equal length, the rollers 34 will be maintained parallel to the mandrel throughout this upward and outward movement.

While the rollers 34 and supporting frame 36 are thus displaced, a can body 20 is moved onto the mandrel, and the actuating arm 43 is swung back to its starting position. As this is done, the roller 44 engages the top of the can and presses it bodily downwardly onto the mandrel. At the same time, the rollers 34 are moved to press against the side walls of the can. As the can is rotated relative to the rollers 34, sufficient pressure is applied manually through the actuating lever 43 to cause dents in the wall of the can to be rolled smooth. At the same time, the can body 20 is pressed axially downwardly on the mandrel by the roller 44, so that lower edges of the rollers 34 may press the extreme edge of the can body 20 against the fillet 22 along the juncture of the rim 21 and the body of the mandrel 19. Sufficient pressure is applied to remove any dents which may have been formed in the edge of the can body 20, and to shape the edge to a slightly outwardly flared condition such as commonly provided on can bodies before the tops are applied.

The straightening rollers 34 are preferably made of vulcanized rubber having a density of about 60-70. The lower ends of the rollers are preferably provided with metal caps 34a machined to conform to the fillet 22, and which act as a die for shaping the flared end of the can. This action is aided by the pressure applied by the roller 44 to press against the closed end of the can body 29, and the resultant force produced by pressure applied by the actuating arm 43 to move the straightening rollers 34 radially toward the axis of the mandrel 19 and axially downwardly along the path defined by the swinging movement of the supporting links 38.

After a can body is straightened, the arm 43 is swung upwardly to permit removal of the straightened can body and the placing of another can body on the mandrel in its place.

While I have shown and described the preferred form of the invention, it is obvious that various changes may be made in its construction by those skilled in the art, without departing from the spirit of the invention as defined in the appended claims.

Having thus described my invention, what I claim and desire to secure by Letters Patent is:

desire to secure by Letters Patent is:

1. A can body straightening machine comprising a power driven shaft adapted to receive any of a plurality of different diameter mandrels shaped to receive a can

body, a mandrel mounted on said shaft and shaped to fit closely within a can body placed thereon and having a rim portion conforming to an expanded edge of the can body, a bracket mounted adjacent the mandrel and shaft, a roller carriage adjustably mounted upon the bracket, a pair of can body straightening rollers and having end portions complementary in shape to the rim portion of said mandrel, means mounting said rollers upon the carriage parallel to the mandrel and shaft for movement axially and radially of said mandrel, an actuating lever mounted upon the carriage for moving the pair of rollers into and out of engagement with and axially of the side wall of a can body upon the mandrel, and a third roller rotatably mounted on said mounting means between said pair of rollers for rotation about an axis perpendicular to the axes of said pair of rollers for engagement with the end of said can, said third roller being adapted to press said can body axially onto said mandrel.

2. A can body straightening machine comprising a main frame, a power driven shaft rotatably mounted in said frame, a mandrel coaxially mounted on said shaft, said mandrel being shaped to fit closely within a can body placed thereon and having a rim portion conforming to an expanded edge of the can body, a carriage, means for adjustably mounting said carriage on said main frame at predetermined spaced distances from the axis of said shaft, a roller frame, a pair of can body straightening rollers having end portions complementary in shape to the rim portion of said mandrel, means rotatably mounting said rollers on said roller frame with the axes of said rollers being parallel to the axis of said shaft and mandrel, link means supporting said roller frame on said carriage for swinging movement of said roller frame through an arcute path while maintaining the axes of said rollers in parallelism to the axis of said shaft and mandrel, said link means including a pair of spaced apart, parallel and equal-length links each pivotally connecting said roller frame to said carriage with the pivotal connections of said links to said carriage being on a line parallel to the axis of said shaft, manually operable means for moving said roller frame through said arcute path to move said rollers into and out of engagement with the side walls of a can body upon said mandrel, and means carried by said roller frame for engaging the end of said can to press said can body axially onto said mandrel as said pair of rollers engages the side walls of said can body.

3. A can body straightening machine comprising a main frame, a power driven shaft rotatably mounted in said frame, a mandrel coaxially mounted on said shaft, said mandrel being shaped to fit closely within a can body placed thereon and having a rim portion conforming to an expanded edge of the can body, a carriage, means for adjustably mounting said carriage on said main frame at predetermined spaced distances from the axis of said shaft, a roller frame, a pair of can body straightening rollers having end portions complementary in shape to the rim portion of said mandrel, means rotatably mounting said rollers on said roller frame with the axes of said rollers being parallel to the axis of said shaft and mandrel, link means supporting said roller frame on said carriage for swinging movement of said roller frame through an arcuate path while maintaining the axes of said rollers in parallelism to the axis of said shaft and mandrel, said link means including a pair of spaced apart, parallel and equal-length links each pivotally connecting said roller frame to said carriage with the pivotal connections of said links to said carriage being on a line parallel to the axis of said shaft, manually operable means for moving said roller frame through said arcuate path to move said rollers into and out of engagement with the side walls of a can body upon said mandrel, and a third roller rotatably mounted on said roller frame between said pair of rollers for rotation about an axis perpendicular to the axes of said pair of rollers for engagement with the end of said can, said third roller being adapted to press said

can body axially onto said mandrel as said pair of rollers
engages the side walls of said can body.
